(57) **CLAIM**

The ornamental design for a USB device, as shown and described.

DESCRIPTION

FIG. 1 is a perspective view of a USB device;

FIG. 2 is a front side view thereof;

FIG. 3 is a back side view thereof;

FIG. 4 is a right side view thereof;

FIG. 5 is a left side view thereof;

FIG. 6 is a top view thereof;

FIG. 7 is a bottom view thereof;

FIG. 8 is a perspective view of the USB depicted in FIG. 1 with the cover removed;

FIG. 9 is a cross section view of the USB device taken at the line 9-9 shown in FIG. 2; and,

FIG. 10 is a bottom view of the USB device with the cover removed and a top view of the removed cover of the USB device.

The broken lines are used for environmental purposes only and form no part of the claimed design.
